UNITED STATES PATENT OFFICE.

RALPH H. ROSENBERG, OF SYRACUSE, NEW YORK, ASSIGNOR TO AMERICAN CABLE COMPANY, INC., A CORPORATION OF DELAWARE.

CABLE BUMPER.

Application filed November 23, 1926. Serial No. 150,194.

This invention relates to bumpers, and more particularly to bumpers of the resilient type, constructed to resist impact, and employing cable or similar flexible members as a whole or part of the impact receiving member.

An object of the invention is to provide a bumper comprising a mat of laterally extending flexible members such as cables held 10 in a suitable clamping device under tension between the ends of a resilient supporting bar, adapted to be secured to a vehicle.

A further object is to provide a bumper of such strength that it will sustain the shock 15 of a considerable impact without injury to the vehicle or obstruction, and which nevertheless presents a light and pleasing appearance.

Another object is to provide a novel method 20 of forming an impact element out of cables by steps which can be carried out quickly and with little expenditure of time and material by relatively unskilled labor, and which will result in the production of a mat 25 of cables accurately aligned and uniform in length and tension.

A clear conception may be had of the structure and objects of this invention from the following description, in conjunction with 30 the accompanying drawings, in which

Fig. 1 discloses one end of the bumper in a plan view.

Fig. 2 is a front view of one end of the bumper.

Fig. 3 is a detail view, taken in the direction of arrow 3, showing an end shoe or holding member with the cables omitted.

Fig. 4 is a detail view in elevation partly in cross section, of the mat of cables, with 40 an attaching member secured thereto.

Fig. 5 is a cross section of the resilient supporting bar.

Fig. 6 is a plan view of the entire bumper.

Fig. 7 shows a machine adaptable for making cable mats.

Fig. 8 is a plan view of Fig. 7.

The now preferred form of bumper comprises an impact element, constituted by a mat of longitudinally extending cables 3, clamped in spaced relation at each end by a transverse block of metal 12.

The mat may be formed by any suitable method, but I have devised a novel method of constructing such impact elements which 55 is preferred by reason of its simplicity and

cheapness, and the accuracy and uniformity of product for which it provides. In pursuance of this important object of the invention the component cables 3 are extended lengthwise in spaced relation side by side, 60 and their ends are passed through suitable apertures 10 in a metal block disposed transversely of the cables. The block, with the cables in place therein, is then compressed by suitable means, as for example by a coin press, until the material of the block, such as soft steel, is compacted into the peripheral helical interstices of the cables, so that the cables and block constitute an integrated structure, as indicated in Fig. 4.

In practice, a number of such blocks may conveniently be first strung upon the cables, and when the end block has been attached as above described, it may be pulled along, drawing with it the cables until the desired 70 length of mat intervenes between the end block and the next block, which is to constitute the connecting member at the other end of the cable mat, and while uniform tension is maintained on each cable to insure uniformity of length and tension, the said next block is similarly compressed, and the cables severed on the outer side of the block, the mat being then complete as a unitary, separable article, ready for installation on the 80 bumper.

The cables may be tensioned by any well-known means, but preferably by clamping each cable to an arm on which is suspended a weight, the length of the arm and the weights 90 being the same for each cable, thereby placing the separate cables under an equal strain.

This cable mat is adapted to be supported under tension by a suitable supporting structure, consisting preferably of a resilient back 95 bar 1, furnished at each end with an arc-shaped shoe or holding member 2. This shoe is formed at 8 with a seat against which the block 12 is positioned, the block being preferably rabbeted at 9 to receive a shoulder 15 formed upon the seat 8, and which aids to prevent displacement of the block 12. Bolts 14 may also be provided to hold the block in place, passing through holes 20 and screwed into sockets 19 formed in the seat 8.

The outer arcuate surface of the shoe is formed with open grooves 4 within which lie the cables 3 in spaced relation, as illustrated clearly in Fig. 2.

The holding member 2 has a slotted portion 110

5, adapted to receive the free end 6 of the resilient supporting bar 1, and bolts 7, serving to hold the member 2 in assembled relation with the bar 1, as shown clearly in Fig. 1.

6 It is to be understood that in Fig. 1, only one end of the bumper structure has been illustrated, and that the complete supporting structure includes a similar holding member 2 at the other end of the bar 1; also that before the cable mat has been applied to these holding members, the bar 1 is bent slightly at its ends so that before applying the mat, the end portions 6 of the bar 1, with their holding members 2 bolted thereto, are flexed forward 15 into approximately the position shown in Fig. 1, and the cable mat is stretched around the holding members 2 and the blocks 12 are seated and secured by the bolts 14, with the portions of the cables 3 near their ends lying 20 in the grooves 4 as shown in Fig. 2.

Then the flexed ends 6 are released, and the resiliency of the bar 1 places the cable mat under tension.

The bumper may then be secured in place 25 upon a vehicle by any suitable form of attachment, which preferably will be applied at approximately the region occupied by the designating numeral 1 in Fig. 1.

The resilient supporting bar is reinforced 30 through its center portion by means of a stiffened rib such as indicated at 18. This rib is of varying depth starting at the ends level with the bar and increasing to a maximum depth at the center, thereby forming a stiff 35 center portion in the bar with the end portions capable of a high degree of resiliency. This rib may be conveniently formed by swaging or stamping the material of bar 1 longitudinally in the shape illustrated in cross section in Fig. 5. It is apparent that the bar might also be made more resiliency at the ends and stiffened in its middle portion by drawing and tapering the ends.

The bumper thus formed comprises but few 45 parts, including the bar 1, which is of very simple, inexpensive structure, being preferably made of a strip of tempered steel, and the two holding members 2, may be castings or forgings which can readily be made without the need for expensive machining, but which may be ground easily and nickelized, or otherwise finished at their exposed surfaces. The bar 1 and the blocks 12 can be readily finished cheaply, as by japanning, and the 50 cables may be finished with a bright or dull finish, as for example by sherardizing, so that the appearance of the bumper as a whole is attractive, and also gives the desirable effect of strength.

60 If desired the cable mat may be provided at suitable intervals with clamps, such as those shown at 16, and these may be disposed in such a manner as to give an ornamental effect.

Fig. 7 discloses a machine which is de- 65 signed to facilitate the making of cable mats.

The machine consists of a bed-plate 21 set on standards 22. At one end is mounted an arm 23 having a screw 24 surmounted by a hand-wheel 25. In the bed, 21, directly below the screw 24 is a slot 26 to accommodate block 12 which is held firmly in position by means of the screw 24.

A die 27 is set in the bed at a pre-determined distance from slot 26 which accommodates the second block 17. This die also has a second recess 34 for compressing a second block similar to 12. This die is a part of a coin-press, the other half being shown at 28. At the far end of the bed from arm 23 is a series of clamping devices 29, with hand-wheels 30, having means to hold each cable separately. Arms 31 are attached to each of the clamps 29 having a circular plate suspended therefrom on which may be added weights, until the correct weight is reached to give the type of cable used a sufficient amount of tension. Each clamping device is pivoted at 37 and is, therefore, free to move under the action of arms 31. A bar 36 is provided which supports the arms when not in use. A guide roller 32, and a storage reel, 33, are provided at the end of the machine for holding a supply of the cable.

As has been described above, the cables 3 are threaded through blocks 12 and 17. Block 12 is then placed in recess 34 and compressed by the coin-press, after which it is drawn forward to recess 26 and clamped in place by wheel 25. The block 17 is then moved along the cable and into position in recess 35 of die 27. All of the cables are now clamped in their respective clamps 29 by means of wheels 30. After all are securely fastened, the bar 36 is withdrawn, allowing the arms 31 to swing free, thereby putting all of the cables under an equal strain. The coin press is now operated and block 17 compressed, after which the ends of the cables outside of block 17 are severed and the mat is complete.

It is apparent that a plurality of mats may be made in sequence in this manner by threading a plurality of blocks onto the cables and compressing the block 12 of one mat at the same time that block 17 of another mat is compressed.

In operation, if an obstruction is hit by the bumper near the center, the cable mat will move inwardly turning the ends of spring 1 toward each other. Owing to the tension of the spring and cable the natural function is to return to normal. As a result the vehicle will sustain the impact with little or no damage to either and the bumper will eventually resume its normal position.

Should the bumper hit an obstruction at or near either end, the adjacent end of the spring 1 will be bent outward and back and the remote end will be turned inward and forward, thereby tending to take up the

shock. When the tension is removed, spring and cables will take up their normal alignment once more.

The cable mat being of flexible material, 5 obviates damage by marring or damaging any object that the bumper may hit, as it takes rather than gives a blow under impact.

I claim:

1. In a bumper of the class described, an 10 impact element comprising a plurality of flexible members having recessed peripheries and extended lengthwise in spaced relation and united by a transverse connecting member compressed upon said flexible members to 15 constitute an integrated structure therewith, the material of said connecting member being indented by, and filling the voids in, said flexible members.

2. In a bumper of the class described, an 20 impact element comprising a plurality of flexible members having recessed peripheries and extended lengthwise in spaced relation and united by a transverse connecting member compressed upon said flexible members 25 permanently to constitute an integrated structure therewith, the material of said connecting member being indented by, and filling the voids in, said flexible members.

3. In a bumper of the class described, an 30 impact element comprising a plurality of flexible members having recessed peripheries and extended lengthwise in spaced relation and united by a transverse connecting member compressed upon said flexible members 35 permanently to constitute an integrated structure therewith, said impact element having a plurality of said transverse connecting members arranged in spaced relation, whereby said flexible members and connecting members 40 constitute a unitary mat structure capable of application to, and removal from, said bumper, as a separable element, the material of said connecting member being indented by, and filling the voids in, said flexible members.

4. In a bumper of the class described, an 45 impact element comprising a plurality of stranded wire cables extended lengthwise in spaced relation and united by a transverse connecting member compressed upon said cables to constitute an integrated structure therewith, the material of said connecting member being indented by, and filling the voids in, said flexible members.

5. In a bumper of the class described, an 55 impact element comprising a plurality of stranded wire cables extended lengthwise in spaced relation and united by a transverse connecting member compressed upon said cables to constitute an integrated structure therewith, the material of said connecting member being indented by, and filling the voids in, said flexible members, said impact element having a plurality of said transverse connecting members arranged in spaced relation.

tion, whereby said cables and connecting members constitute a unitary mat structure capable of application to and removal from, said bumper, as a separable element.

6. In a bumper of the class described, an 70 impact element comprising a plurality of stranded wire cables extended lengthwise in spaced relation and united at their adjacent ends by a transverse connecting member of relatively softer metal, compressed upon said ends to constitute an integrated structure therewith, the material of said connecting member being indented by, and filling the voids in, said flexible members.

7. In a bumper of the class described, an 75 impact element comprising a plurality of stranded wire cables extended lengthwise in spaced relation and united at their adjacent ends by a transverse connecting member of relatively softer metal, compressed upon said ends to constitute an integrated structure therewith, the material of said connecting member being indented by, and filling the voids in, said flexible members, said impact element having a plurality of said transverse 80 connecting members arranged near the respective ends of the cables, whereby said cables and connecting members constitute a unitary 85 mat structure capable of application to and removal from, said bumper, as a separable element.

8. In a bumper of the class described, an 90 impact element comprising a plurality of stranded wire cables extended lengthwise in spaced relation and united by a transverse connecting member of relatively softer metal, having transversely spaced apertures to receive said cables, the material of said connecting member being compressed upon said cables to constitute an integrated structure 95 therewith.

9. In a bumper of the class described, an 100 impact element comprising a plurality of stranded wire cables extended lengthwise in spaced relation and united by a transverse connecting member of relatively softer metal, having transversely spaced apertures to receive said cables, the material of said connecting member being compressed upon said cables and entering the peripheral interstices 115 thereof, to constitute an integrated structure therewith, said impact element having a plurality of said transverse connecting members arranged in spaced relation, whereby said cables and connecting members constitute a 120 unitary mat structure capable of application to and removal from, said bumper, as a separable element.

10. In a bumper of the class described, an 125 impact element comprising a plurality of stranded wire cables extended lengthwise in spaced relation and united at their adjacent ends by a transverse connecting member of relatively softer metal, compressed upon said ends and entering the peripheral inter- 130

stices thereof, to constitute an integrated structure therewith, said impact element having a plurality of said transverse connecting members arranged near the respective ends of the cables, whereby said cables and connecting members constitute a unitary mat structure capable of application to and removal from, said bumper as a separable element, and a resilient supporting bar adapted to be connected to a vehicle and having means to hold said cable mat under tension.

11. In a bumper of the class described, an impact element comprising a plurality of flexible members, such as cables extended lengthwise in spaced relation and united at their adjacent ends by a transverse connecting member; a resilient supporting bar adapted to be secured to a vehicle; and a holding member having a seat to receive said connecting member, and a slot to receive said supporting bar, and means to hold said parts in assembled relation.

12. In a bumper of the class described, an impact element comprising a plurality of flexible members such as cables or chains extended lengthwise in spaced relation and united at their adjacent ends by a transverse connecting member; a resilient supporting bar adapted to be secured to a vehicle; and a holding member having a seat to receive said connecting member, and a slot to receive said supporting bar, and means to hold said parts in assembled relation, said holding member having spaced grooves within which said flexible members lie when said parts are assembled.

13. In a bumper of the class described, an impact element comprising a plurality of flexible members extended lengthwise in spaced relation and united at their adjacent ends by transverse connecting members; a resilient supporting bar adapted to be secured to a vehicle; a pair of holding members each having a seat to receive a connecting member,

and a slot to receive an end of said supporting bar, and means to hold said parts in assembled relation; and means for locking said connecting members to said seats when the ends of the supporting bar are under tension.

14. In a bumper of the class described, an impact element comprising a plurality of flexible members extended lengthwise in spaced relation and united at their adjacent ends by transverse connecting members; a resilient supporting bar adapted to be secured to a vehicle; and a pair of holding members each having a seat to receive one of said connecting members and a slot to receive said supporting bar, said resilient supporting bar having its middle portion formed with a stiffening rib to limit its resiliency, and having its ends bowed and held by said impact element maintaining it under tension.

15. In a bumper of the type described, an impact element comprising a plurality of flexible members extended lengthwise in spaced relation and united at their adjacent ends by transverse connecting members; a resilient supporting bar adapted to be secured to a vehicle, and a pair of holding members each having a seat to receive one of said connecting members and a slot to receive said supporting bar, said resilient supporting bar having its middle portion formed with a stiffening rib of varying depth to limit its resiliency and having its ends bound and held by said impact element maintaining it under tension.

16. In an automobile bumper an impact element, a resilient supporting bar adapted to be secured to a vehicle, said supporting bar having its middle portion formed with a stiffening rib of varying depth to limit its resiliency.

In testimony whereof, I have signed this specification.

RALPH H. ROSENBERG.
